UNITED STATES PATENT OFFICE

NORMAN D. LANSDOWN, OF WILMINGTON, DELAWARE, ASSIGNOR TO STANDARD-TRUMP BROS. MACHINE COMPANY, OF WILMINGTON, DELAWARE, A CORPORATION OF DELAWARE

CIRCULAR-KNITTING MACHINE

Application filed January 25, 1929. Serial No. 334,920.

My invention relates to machines for knitting hosiery and particularly to mechanism for so manipulating the yarns during each course, while rotatably knitting the foot of the stocking, that the yarn which is knit in the sole will be different from the yarn or yarns which is knit in the upper portion. The ordinary mechanism comprises separate yarn feeds, or guides, or fingers, for the main 5 yarn and sole yarn respectively, and means for operating each of them independently. The ordinary method of operation comprises so oscillating these guides that each guide feeds its yarn to the needles for approximately half a revolution and withholds its 10 yarn from engagement with the needles for approximately half a revolution, the two guides being rendered active alternately. It is customary, also, to render each guide 15 active just after the other guide is rendered active so that the two yarns overlap on each side of the foot on two or three needles.

When striped effects are produced in the leg and in the upper half of the foot, in combination with a plain sole, two or more guides, in addition to the sole yarn guide, one for each striping yarn, are employed. One of these guides, which carries the yarn which overlaps the sole yarn as above described, 20 may be considered a main yarn guide. This renders it necessary to provide means for oscillating each of these guides. In knitting the foot, the usual method necessitates special mechanism for moving and holding the striping 25 yarn guides out of action during each half revolution of the machine while knitting the sole.

My invention has for its object to avoid the necessity of specially oscillating the striping 30 yarn guides to provide for the knitting of a plain sole. The object of the invention is accomplished by rendering the striping yarn guides inoperative to feed yarn to the needles during the knitting of the sole, whether any or 35 all of them are, intermittently or continuously, then in yarn-feeding position. This object is accomplished, preferably, by mechanism which, in each course of knitting, renders such striping yarn guides inoperative, if 40 they, or any of them, are in yarn feeding position,

tion, when, or just after, the sole yarn guide is moved into active or yarn-feeding position and which maintains them inoperative during the knitting of a half course and which renders them operative, if they, or any of them, are in yarn-feeding position, when, or just before, the sole yarn guide is moved into inactive or yarn-withdrawal position. This mode of operation dispenses with the necessity of any special oscillation of the striping 55 yarn guides during the knitting of the entire foot. Further, during the knitting of the foot, the striping yarn guides may be manipulated as if the back of the leg were being knit, without effecting any insertion of yarn 60 in the sole. This permits of a substantial simplification of the pattern controlled mechanism which effects the timed oscillations of the various striping yarn guides.

In the preferred embodiment of the invention, a single cam oscillates the sole yarn guide and a member, preferably a yarn-deflecting wire, renders the other yarn guides inoperative to feed yarn even though they, or any of them, may be in operative position, the deflecting wire being moved into operative position approximately when the sole 70 yarn guide is moved into operative position and being moved out of operative position approximately when the sole yarn guide is moved out of operative position; provision being made to effect the above described overlap of main yarn and sole yarn at opposite sides of the foot. The deflecting wire, when moved into operative position, is interposed 75 between the needles and the yarn fingers which carry the striping yarns and lifts into, and holds in, inactive position any yarn which would otherwise feed to the needles.

The mechanism devised by me has also the advantage of insuring that a precise predetermined number of wales of overlapping yarns will always be knit into the fabric at opposite sides of the foot where the top joins the sole.

A preferred embodiment of the mechanism of the invention is shown in the accompanying drawings, in which:—

Fig. 1 is a side elevation of part of a knitting machine embodying my invention.

Fig. 2 is a front view of part of the mechanism of Fig. 1.

Fig. 3 is a detail perspective view of the levers for actuating the sole yarn guide and yarn deflector.

Fig. 4 is a perspective view of the mechanism of Fig. 1, the parts being spaced apart in order to more clearly illustrate them.

Fig. 5 is a plan view of the cam for actuating the levers of Fig. 3.

Fig. 6 is a diagram of a stocking having certain parts thereof knit with a special thread.

Vertically slidable in the rotatable needle cylinder *a* are the needles *b* which travel through the usual knitting wave and cooperate with sinkers *c* to form loops of fabric. A sole yarn is fed to the needles by guide *d* and striping yarns are carried by guides *e*, *f* and *g*. When the guides are down in active position, their respective yarns pass over the latch ring *h* to the needles.

Yarn guides, *e*, *f* and *g* are pivoted on a common stud *i* and are moved down to active position and up to inactive position by any suitable mechanism, such, for example, as that disclosed in Patent No. 1,161,677, issued November 23, 1915, to Harold E. Houseman. Retainers *j*, one for each of the three guides, drop into notches and hold their respective guides either in active or inactive position.

The sole yarn guide *d* is pivoted on a stud *k* and has a spring *m* which tends to draw it down into active position. A lever *n* is capable of lifting the sole guide *d* against the pull of its spring to inactive position. Pivoted on the same stud *k* is a member *o* carrying a deflecting wire *p* which underlies all yarns feeding from yarn guides *e*, *f* and *g* to the needles, and which, when elevated by a spring *q*, causes the wire *p* to deflect any yarn which may be feeding from one of the guides to a position where it will fail to engage the needles. This member *o* is rendered inactive to deflect yarns by the action of a lever *r*. Both levers *n* and *r* are pivoted on a common stud *s* and carry on their lower ends rollers *t* and *u* respectively. A single arcuate cam *v* carried on the needle cylinder, which revolves in the direction indicated by the arrow on Fig. 5, operates rollers *u* and *t* and thereby, through their respective levers *r* and *n*, actuates the deflecting wire *p* carried by member *o* and the sole guide *d*.

Let it be assumed that the sole is being knit, at which time the sole yarn guide *d* and the deflecting finger *p* are in positions opposite to those shown in Figs. 1 and 4: the sole yarn guide being down in yarn feeding position and the finger *p* being up in yarn deflecting position. At the conclusion of the half course of sole knitting the forward end of the revolving cam *v* engages

roller *u* of lever *r* and pushes it outward, thereby causing lever *r* to lower the deflecting wire *p*, permitting the yarn, feeding from main guide *e*, which is in yarn feeding position, to engage the needles.

Cam *v* then engages roller *t* of lever *n*, pushing it outward, thereby causing sole yarn guide *d* to be lifted, and disengaging the sole yarn from the needles. During the next half course of knitting, cam *v* holds both sole yarn guide *d* and yarn deflecting finger *p* out of operative position, permitting yarn to be fed from any or all of the fingers *e*, *f* and *g* that at any time may be down in yarn feeding position. At the conclusion of the last named half course of knitting, main yarn guide *e* being down in operative position, the rear end of the cam *v* passes from under rollers *u* and *t*, permitting springs *q* and *m* of member *o* and guide *d* to function, whereby the deflecting wire *p* is elevated, disengaging from the needles the yarn from guide *e*, and guide *d* is moved down so that it will feed the sole yarn to the needles. It is obvious that any yarn or yarns which may be feeding to the needles from any of guides *e*, *f*, and *g* will be under control of the deflecting wire *p* and that the guides may remain stationary.

In order to prevent defective knitting along opposite sides of the foot, it is necessary that each yarn be engaged by the needles before the other is withdrawn. It is, therefore, important that the main and sole yarns should overlap on two or three needles at either side. The mechanism described effects this result insofar as concerns the introduction of the main yarn to the needles in advance of the withdrawal of the sole yarn, because the forward end of cam *v* engages rollers *u* and *t* successively and not simultaneously. The rear end of the cam, however, releases roller *u* in advance of roller *t* and therefore, without special provisions to prevent it, the main yarn would be withdrawn in advance of the introduction of the sole yarn to the needles, thereby causing holes to appear in the fabric. This operation is, however, prevented by a pin *w* carried by lever *n* and which bears against lever *r* and which prevents any movement of deflecting wire member *o* by its spring to withdraw a main yarn until such time as the cam passes by roller *t*. Therefore, although sole yarn guide *d* is moved into action simultaneously with the withdrawal of finger *p*, the first two or three needles that travel past the sole yarn guide after its movement into action have previously engaged the main yarn, so that these needles knit both yarns into the fabric.

The construction described has the pronounced advantage that in the operation of knitting the circular body of the foot, all the yarns are controlled by a single cam.

It should be understood that while one use of my invention is to avoid the necessity of specially oscillating the striping yarn guide to provide for knitting the plain sole of a complete stocking, my invention is not limited to this use, but is intended and adapted broadly for use in the knitting of any circular fabric in which one yarn knits for approximately one half a course and another 5 yarn for the other half course. I have, therefore, not disclosed such mechanism as would be necessary for holding the yarn guide *d* up out of yarn feeding position and the deflecting wire *p* down in inoperative position during the knitting of the leg, heel and toe portions of a stocking. Such mechanism can be supplied by one skilled in the art, without the exercise of invention, if it is desired to apply the invention to such use. 10 To knit the circular fabric described, no mechanism other than that herein shown and described is necessary.

What I claim and desire to protect by Letters Patent is:

25. 1. In a circular knitting machine equipped with a yarn guide movable into position to feed yarn to the needles and another yarn guide adapted also to feed yarn to the needles, the process of knitting only the second 30 yarn into the fabric which comprises moving into and maintaining in yarn feeding position the second named yarn guide during the knitting of approximately half a course and then withdrawing it, and during 35 the knitting of approximately the same half course deflecting the yarn carried by the first named yarn guide while in yarn feeding position so that such yarn will not feed to the needles.
40. 2. In a circular knitting machine equipped with a yarn guide movable into position to feed yarn to the needles and another yarn guide adapted also to feed yarn to the needles, the process of knitting only the second 45 yarn into the fabric which comprises moving into and maintaining in yarn feeding position the second named yarn guide during the knitting of approximately half a course and then withdrawing it, and during the knitting 50 of approximately the same half course deflecting the yarn carried by the first named yarn guide so that it will feed yarn only to the first one or more needles and the last one or more needles which knit the said half course.
55. 3. In a circular knitting machine, the combination with a rotatable needle cylinder and needles carried thereby, and two yarn guides, one of which is movable into and out of yarn feeding position, of a deflector movable into and out of position to deflect yarn fed by the other yarn guide, when in yarn feeding position, from engagement with the needles, while the movable yarn guide is feeding yarn, and means to synchronously move the first yarn guide and the deflector 60 65

into operative position and out of operative position.

4. In a circular knitting machine, the combination with a rotatable needle cylinder and needles carried thereby, a yarn guide, and another yarn guide movable into and out of yarn feeding position, of a deflector movable into and out of position to deflect yarn fed by the first named yarn guide, when in yarn feeding position, from engagement with the needles, a cam rotatable with the needle cylinder, and cam-controlled connections adapted to synchronously effect a movement of the second named yarn guide and the deflector into operative position at approximately the beginning of each alternate half course of knitting and out of operative position at approximately the end of such half course. 70 75 80

5. In a circular knitting machine, the combination with a rotatable needle cylinder and needles carried thereby, a yarn guide, and another yarn guide movable into and out of yarn feeding position, of a finger extending in front of the first named yarn guide and movable into and out of position to deflect from engagement with the needles yarn fed from the first named yarn guide when in yarn feeding position, while the movable yarn guide is feeding yarn, and means to synchronously move the second named yarn guide and said finger into operative position and out of operative position. 85 90 95

6. In a circular knitting machine, the combination with a rotatable needle cylinder and needles carried thereby, a yarn guide, and another yarn guide movable into and out of yarn feeding position, of a finger extending in front of the first named yarn guide and movable into and out of position to deflect from engagement with the needles yarn fed from the first named yarn guide when in yarn feeding position, an arcuate cam rotatable with the needle cylinder, and connections controlled by said cam and adapted to synchronously effect a movement of the second named yarn guide and said finger into operative position at approximately the beginning of each alternate half course of knitting and withdrawal of the second named yarn guide and said finger out of operative position at approximately the end of each such half course. 100 105 110 115

7. In a circular knitting machine, the combination with a rotatable needle cylinder and needles carried thereby, a yarn guide, and another yarn guide movable into and out of yarn feeding position, of a deflector movable into and out of position to deflect yarn fed by the first named yarn guide, when in yarn feeding position, from engagement with the needles, means controlling the movement of the second named yarn guide into and out of yarn feeding position, 120 125 130

means controlling the movement of the deflector into and out of operative position, and a common device adapted to so actuate both means at substantially opposite points in each circular course of knitting as to render the yarn fed by the second named yarn guide operative to knit on approximately a semi-circumference of needles and render the deflector operative to deflect yarn from all of said needles except the needles at opposite ends of said semi-circumference.

8. In a circular knitting machine, the combination with a rotatable needle cylinder and needles carried thereby, of a yarn guide, and another yarn guide movable into and out of yarn-feeding position, of a deflector movable into and out of position to deflect yarn fed by the first named guide, when in yarn feeding position, from engagement with the needles, a lever controlling the movement into and out of operative position of the second named yarn guide, a second lever controlling the movement into and out of operative position of the deflector, and an arcuate cam rotatable with the needle cylinder and adapted to operate the second and first levers successively to effect the successive movement out of operative position of the deflector and the second named yarn guide.

9. In a circular knitting machine, the combination with a rotatable needle cylinder and needles carried thereby, of a yarn guide, and another yarn guide movable into and out of yarn feeding position, of a deflector movable into and out of position to deflect yarn fed by the first named guide, when in yarn feeding position, from engagement with the needles, a lever controlling the movement into and out of operative position of the first named yarn guide, a second lever controlling the movement into and out of operative position of the deflector, and an arcuate cam rotatable with the needle cylinder and adapted to operate the second and first levers successively to effect the successive movement out of operative position of the deflector and the second named yarn guide and adapted to release said second and first levers successively, and a stop controlled by the first lever and preventing the withdrawal of the second lever to effect a movement into operative position of the deflector until the release of the first lever to effect a movement of the second named yarn guide into operative position.

In testimony of which invention, I have hereunto set my hand, at London, England, on this 17th day of December, 1928.

NORMAN D. LANSDOWN.
